UNITED STATES PATENT OFFICE.

NEWTON ROGERS AND JAMES A. WHARRY, OF TERRE HAUTE, INDIANA.

APPARATUS FOR VAPORIZING OIL AND WATER AND SUPERHEATING AND BURNING THE SAME.

SPECIFICATION forming part of Letters Patent No. 407,901, dated July 30, 1889.

Application filed March 21, 1889. Serial No. 304,139. (No model.)

To all whom it may concern:

Be it known that we, NEWTON ROGERS and JAMES A. WHARRY, of Terre Haute, in the county of Vigo and State of Indiana, have invented certain new and useful Improvements in Apparatus for Vaporizing Oil and Water and Superheating and Burning the Same; and we do hereby declare that the following is a full, clear, and exact description of the invention, which will enable others skilled in the art to which it appertains to make and use the same, reference being had to the accompanying drawings, and to the letters of reference marked thereon, which form part of this specification.

Our invention relates to an improvement in apparatus for vaporizing oil and water and superheating and burning the same; and it consists in certain novel features of construction and combinations of parts, more fully described hereinafter, and particularly pointed out in the claims.

Referring to the accompanying drawings, Figure 1 represents a perspective view of our apparatus; Fig. 2, a longitudinal central section of the same; and Fig. 3 an end elevation, partly in section, showing the three cylinders connected.

In the drawings, the reference-letters *a b c* indicate three cylindrical closed retorts or chambers strongly constructed, preferably of wrought-iron or other metal. These cylinders are preferably parallel and located closely side by side, leaving spaces between the same, with the middle chamber or retort *b* in a lower plane than the other two retorts. These retorts are firmly braced and secured together by one or more encircling-yokes *d*, each preferably cast in one piece and encircling the three retorts and provided with loops or openings in which each retort rests, as shown.

The retort *a* is provided with an oil-supply pipe *e*, opening into one end of the same, and this oil-supply pipe is provided with a valve to regulate the flow of oil into this oil-vaporizing retort *a*. The opposite end of the oil-vaporizing retort is connected with one end of the superheating and commingling chamber *b* by a short pipe *f*. A water-supply pipe *g*, provided with a regulating-valve, extends into one end of the water-vaporizing chamber *c*, preferably at the end opposite the oil-

entrance end of the oil-vaporizing chamber, and the opposite end of the water-vaporizing chamber is connected with the end of the mixing-chamber opposite that connected with the oil-vaporizing chamber by means of a short pipe *h*. A vertical pipe or conduit *i* extends downwardly from and opens into the bottom of the mixing and superheating retort and forms a support for the three retorts. This gas-pipe or conduit passes through and rests upon a supporting pan and base *j*, located directly beneath the retorts and preferably provided with legs to hold it above the article upon which it rests. On the upper side of the pan the gas-pipe *i* is provided with a union *k*, by means of which two or more pipes or burners *l* are secured to and are in communication with the gas-supply pipe, and these burner-pipes extend horizontally over the pan and beneath the middle mixing-retort and are closed at their outer ends and provided with a series of apertures through their upper sides beneath said retort. The portions of the pipes provided with the apertures are straddled or covered by removable hoods or burner-caps *m*, provided with flame-openings *n* above the apertures *l* and beneath the retorts. These hoods are provided with slots in their sides (see Fig. 1) to allow them to straddle the burner-pipes, while their lower edges rest directly upon the pan and surround flanges *o*, extending upwardly around openings *o* through the bottom of the pan, thereby forming air and vapor mixing and combustion chambers around the burners. The lower end of the gas-conduit extends through the bottom of the pan and is screw-threaded, as shown, to screw into an opening in the top of a removable metal chamber *p*, (see Fig. 2,) located directly beneath the pan, and for the purpose herein-after appearing.

In operation the water is passed into the vaporizing-retort *c* through the pipe *g*, and is therein converted into steam, and passes from the opposite end of the retort into one end of the middle mixing-retort through short pipe *h*. The oil is supplied into the oil-vaporizing retort *a* through pipe *e*, and the hydrocarbon vapor is passed from this retort into the opposite end of the gas-mixing chamber *b* through pipe *f*. In this retort *b* the steam

and hydrocarbon vapor are superheated, mixed, and commingled by their own pressure, and pass down through the gas or vapor supply pipe *i* to the burner-pipes and out of 5 the series of apertures in the same, where they are consumed. The burner caps or hoods *m* form combustion-chambers, in which the air and gas or vapor are confined to effect perfect combustion and draw in a plentiful 10 but not too great supply of air through the openings in the pan, thereby avoiding all smoke and smell by reason of the perfect combustion of the gas or vapor. The closed trap, chamber, or reservoir *p* on the lower end 15 of the gas-pipe *i* receives all the coal-tar, asphalt, and residuum from the distillation of the oil and water, and can be taken off at any time and emptied without disarranging the apparatus in any way. One of the great dis- 20 advantages of the hydrocarbon-burners heretofore in use is that they can be used but a short while without becoming clogged and gummed up with residuum, and by continued burning this residuum becomes hard and ren- 25 ders the machine useless; but in this present apparatus there is perfect drainage throughout the entire device, the mixing-retort being lower than the two retorts discharging into the same and the gas-supply pipe extending 30 down from the bottom of the mixing-retort and provided on its lower end with the removable reservoir, into which all the residue drains. The pan beneath the retorts and burners not only forms a base for the appa- 35 ratus, but is intended to receive asbestos, &c., which is intended to be saturated with oil for generating sufficient gas to start the apparatus, and after sufficient gas or vapor has been generated for consumption at the burners the 40 operation can be kept up continuously as the burners heat the retorts.

One great advantage of this apparatus is its extreme simplicity of construction, being so put together that any one can take it apart. 45 It is preferably constructed of wrought-iron, and hence is exceedingly durable and not liable to crack, and, further, all pulsation and irregularities of the flame are prevented, as the water and oil are vaporized in different 50 retorts and the gases superheated and mixed in another retort before passing to the burner.

The water-vaporizing chamber can, if desired, be filled with pulverized coke, iron-sponge, or any other carbon for the water and 55 steam to pass through, thereby carbureting the same and rendering it more combustible.

What we claim is—

1. In an apparatus for vaporizing oil and water and superheating and burning the 60 same, the combination of an oil-vaporizing retort provided with an oil-supply, a water-vaporizing retort provided with a water-sup- 65 ply, a separate and distinct mixing and superheating retort communicating directly by suit- able means with said vaporizing-retorts and located in a lower plane than the vaporizing-retorts, whereby intervening spaces are formed

for the flame, a gas-pipe leading from said mixing-retort, and one or more burners below the superheating-retort, substantially as- 70 described.

2. In an apparatus for vaporizing oil and water and superheating and burning the same, the combination of the parallel oil and water vaporizing retorts, a separate mixing 75 and superheating retort located between and in a plane below said vaporizing-retorts, pipes connecting the superheating-retort and the vaporizing-retorts, a vapor-pipe extending down from the mixing-retort and provided 80 with burners located beneath said retorts, and a base, substantially as described.

3. The combination, with the oil and water vaporizing retorts and a separate mixing and superheating retort located in a lower plane 85 than and into which the gases from said vaporizing-retorts are passed, of a vapor-pipe leading down from the bottom of said mixing-retort, burners supplied from said pipe, and a trap or reservoir removably secured on the 90 lower end of said pipe, whereby the residuum is drained from said retorts into said reservoir, substantially as described.

4. In an apparatus for vaporizing and burning oil and water, the combination of a base 95 having air-supply openings therethrough, wa- ter and oil vaporizing retorts, a vapor mixing and superheating retort above the base and in communication with said vaporizing-retorts, a vapor-exit pipe leading from the mix- 100 ing-retort to the base and provided with lateral burner-pipes extending therefrom over the base, and burner-caps straddling said burner-pipes, having their lower open ends resting on the base over said air-supply open- 105 ings and having flame-openings above the burners, whereby mixing and combustion chambers are formed around the burners, sub- stantially as described.

5. The combination of separate water and 110 oil vaporizing retorts, supply-pipes for the same, a mixing-retort, pipes connecting the va- porizing-retorts with the mixing-retort, yokes 115 securing said retorts together, a vapor-exit pipe extending down from the mixing-retort and provided with one or more burner-pipes 120 extending from the same beneath the retorts, substantially as described.

6. The combination of an oil-vaporizing re- 120 tort provided with a supply-pipe, a water-vaporizing retort provided with a supply-pipe, a mixing and superheating retort located be- 125 tween and parallel with said two retorts and in a plane below the same, pipes extending down from the vaporizing-retorts to the mix- ing-retort, a pipe extending downwardly from the bottom of the mixing-retort and having its lower end provided with a trap or cham- ber, and burners extending laterally from said pipe beneath the retort, substantially as de- 130 scribed.

7. The combination of a pan, an oil-vapor- 130 izing retort provided with a supply, a water-vaporizing-retort provided with a supply, a

mixing-retort in communication with the vaporizing-retorts, said retorts being secured together and supported above the pan, a gas-pipe extending down from the mixing-retort 5 and provided with a removable trap or reservoir on its lower end, pipes extending laterally from the gas-pipe beneath the retorts and provided with apertures, and burner caps or hoods surrounding said apertures, substantially as described.

In testimony that we claim the foregoing as our own we affix our signatures in presence of two witnesses.

NEWTON ROGERS.
